UNITED STATES PATENT OFFICE

102,616

DESIGN FOR A CARPET UNDERLINER

Nathaniel Newman, Chicago, Ill.

Application October 19, 1936, Serial No. 65,348

Term of patent 14 years

To all whom it may concern:

Be it known that I, Nathaniel Newman, a citizen of the United States of America and residing at Chicago, in the county of Cook and State of Illinois, have invented a new, original, and ornamental Design for Carpet Underliner, of which the following is a specification, reference being had to the accompanying drawing, forming a part thereof.

In the drawing,

Fig. 1 is a top plan view of the carpet underliner showing a portion of the tread surface embodying my design.

Fig. 2 is a section taken on the line 2—2 of Fig. 1.

Referring now to the drawing, the carpet underliner comprises the ribs *a* which are upraised from the base proper, the high point of the ribs being shown in white on Figure 1. The sides of these ribs are substantially perpendicular and not greatly tapered, and there is thus presented elevations and depressions, producing the design substantially as shown in the drawing.

What I claim is:

The ornamental design for a carpet underliner as shown and described.

NATHANIEL NEWMAN.
